HYDRAULICALLY DRIVEN TRANSIT MIXER
John W. Lendved, Wauwatosa, Wis., assignor to Chain
Belt Company, Milwaukee, Wis., a corporation of Wis-
consin

Filed Apr. 1, 1959, Ser. No. 803,387
11 Claims. (Cl. 259—171)

This invention relates generally to transit concrete mixers and more particularly to a truck-mounted mixer having an improved power transmitting and control apparatus for driving the mixing drum.

Concrete mixers are conventionally mounted on the rear portion of a motor truck for transporting batches of concrete from a central source. The concrete mixers are rotatably mounted for mixing or agitating the concrete during the travel to the consumer.

Truck-mounted concrete mixers are so arranged that the mixing drum is either driven by a separate engine carried on the truck or by the internal-combustion engine of the truck.

The driving power for truck engine driven mixing drums may be taken indirectly from the truck engine through the main clutch and the usual power transmission mechanism or directly from the crankshaft of the engine. In the indirect power take-off, the speed of rotation of the mixing drum is directly related to the speed of the truck. Furthermore, when the main clutch is disengaged to shift the truck gears, the mixing drum stops rotating and must be restarted upon re-engaging the clutch. This makes gear shifting difficult. Furthermore, the mixing drum often turns backwards when the clutch is disengaged because of the unbalance load in the drum and interferes with rapid clutching and shifting of the truck. With such previously used mixer driving arrangement, the truck operator is not therefore free to utilize the truck motor to best advantage, particularly when difficult driving conditions demand flexibility of operation and full power.

Some of the difficulties involved in the indirect power take-off from the truck engine to drive the mixing drum have been obviated by arranging a power take-off connection directly to the engine without going through the main clutch.

Such connections are usually made at the front end of the truck engine where the crankshaft can be most readily connected to a separate transmission train. However, the transmission trains are relatively complicated and troublesome to install on the truck. Furthermore, truck mixers are mounted on commercial trucks of various kinds, and even though the trucks are quite similar in appearance and basic construction, differences in details of construction necessitate special mounting arrangements in adapting the mixer drum drive mechanism to each individual truck. This makes it difficult and usually impractical to transfer a mixer from trucks of one manufacturer to another.

A separate engine mounted on the truck for driving the mixer is therefore widely used.

The United States Patent 2,696,371 to J. W. Lendved discloses an improved and highly satisfactory separately mounted engine drive. As more fully disclosed therein, practically all governmental units establish weight limits than can be carried on the truck wheels of trucks employing the highways. Normally, the rear wheels are loaded to capacity prior to the front wheels. If a portion of the load can be shifted to the front wheels, an increased total load can be carried. The Lendved patent provides a separate engine mounted adjacent the rear portion of the truck to shift maximum weight onto the front wheels.

Separate engines require suitable gear reduction and coupling to the mixing drum and normally substantially

2

increase the basic weight of the truck and mixer and reduce the pay load which can be carried in the mixer.

A mechanical drive coupling the drum to the truck engine or to a separate internal-combustion engine are practically exclusively employed in present commercial truck-mounted mixer. However, hydraulic drives for truck-mounted mixer are also available.

The known hydraulic drives generally employ a high speed hydraulic motor which is coupled to the mixing drum by a suitable gear or chain reduction system. The drives are relatively complicated and heavy. Consequently, such drives reduce the payload which can be carried and are relatively expensive in first cost and maintenance. Further, when the direction of rotation of the drum is to be quickly reversed the inertia in the drum establishes relatively large shock forces on the coupling system.

It is therefore a general object of the present invention to provide an improved truck-mounted concrete mixer having an improved power transmitting system for driving the mixing drum of the concrete mixer.

Another object of the invention is to provide an improved mixing drum driving apparatus that may be installed readily on any of various supporting vehicles and which establishes excellent distribution of the payload between the several wheels.

Another object is to provide an easily controlled and smoothly operating lightweight power transmission mechanism for driving the mixing drum of a truck mixer from the truck engine.

Another object of the invention is to provide an improved hydraulically actuated power transmission mechanism for driving the mixing drum of a truck mounted concrete mixer from the engine of the truck.

Another object is to provide a combined driving motor and main bearing pedestal unit for the mixing drum of a truck mixer.

Another object is to provide an improved truck mounted mixer driving arrangement including a reversible, variable speed motor directly connected to the mixing drum.

Another object is to provide a directly connected driving motor for a concrete mixing drum so arranged that mixing water may be introduced into the drum through the shaft of the motor.

According to the invention, a truck mounted concrete mixer is provided with an improved power transmitting apparatus whereby the mixing drum may be readily driven from the truck engine or other power source preferably in either direction of rotation and at any desired speed within a preselected operating range. The improved apparatus of the present invention is hydraulically operated, is lightweight, directly and smoothly controlled through a suitable hydraulic flow control system and may be installed readily on trucks of various kinds.

The hydraulic transmission system in accordance with a preferred construction includes an efficient slow-speed reversible hydraulic motor that is mounted at the front of the drum and is directly connected to the drum head. Hydraulic fluid under high pressure is supplied to the motor through suitable flexible conduits from a variable-displacement, reversible-flow pump that is driven preferably by the truck engine. The hydraulic motor is of the multiple-cylinder, radial type and its power shaft is connected to the drum head to constitute the mixer shaft. The motor bearings form the main bearing for the drum with the motor housing serving as the front bearing pedestal. Since the fluid is pumped at high pressure, the required power may be transmitted at low velocity thereby minimizing power losses and improving operating conditions. A simple control device mounted in the truck cab or elsewhere on the machine may be operated to adjust the pump for effecting rotation of the mixing drum in either direction at a selected speed.

In accordance with another aspect of the present invention, the motor is supported on the truck at a single point by means of a universal pivot support or ball joint to correspondingly support the adjacent end of the drum. The opposite end of the drum is supported in the usual manner on a pair of spaced rollers. The rollers and the ball-type joint establishes a three-point mounting system for the mixing drum which avoids stresses which might otherwise result from bending and twisting of the truck frame in operating over rough terrain.

The ball-type joint end of the drum is stabilized on its single support point by a torque resisting or stabilizing strut that is inter-connected between the motor and the truck frame to prevent lateral swinging movement of the drum.

Since the motor is directly connected to the drum end, it requires little space thereby enabling the drum to be positioned forwardly on the truck for best weight distribution.

The hydraulic fluid circulates in a closed circuit between the pump and the motor, the circuit being so arranged that the motor operates also as a brake to keep the drum always under control whereby the drum may be started smoothly, reversed or stopped with minimum shock. Since the power connection between the truck engine and the drum driving motor may be effected through flexible conduits, the apparatus may be mounted in the most favorable positions on any suitable motor truck or transferred from one truck to another and the conduits installed with minimum modification of the truck structure.

The foregoing and other objects of this invention will become more fully apparent from the following detailed description of a preferred embodiment of an improved truck mounted concrete mixer constructed in accordance with the present invention.

The drawings furnished herewith illustrate the best mode presently contemplated for carrying out the invention.

In the drawings:

FIG. 1 is a side elevational view with parts broken away of a truck-mounted concrete mixer incorporating a preferred embodiment of the mixer drive in accordance with the present invention;

FIG. 2 is the fragmentary view taken upon a line 2—2 of FIG. 1;

FIG. 3 is a view partly in section and partly in elevation generally taken on line 3—3 of FIG. 2;

FIG. 4 is a front elevational view of the hydraulic motor shown in FIGS. 2 and 3 with the principal plane of the motor pivoted to a vertical plane;

FIG. 5 is a cross section of a fluid distributing valve shown in FIGS. 1—3; and

FIG. 6 is a simplified diagrammatic circuit of the hydraulic power system adapted to the drive shown in FIGS. 1—5.

Referring to the drawings and particularly to FIG. 1, a truck mounted concrete mixed constructed in accordance with the present invention is shown generally including a mixing drum 1 which is rotatably mounted on the rear portion of a truck frame 2 of a conventional type truck 3 to form a truck mounted transit mixer adapted for delivery and mixing of concrete, not shown.

The truck includes a pair of forward front steering wheels 4 and tandem rear wheels 5 which are connected to the frame 2 in any suitable manner to allow movement of the truck 3. The frame 2 conventionally consists of a pair of laterally spaced longitudinally extending channel members which are interconnected to form a rigid and firm understructure for supporting the various operating members of the truck and the mixing drum. An internal-combustion engine 6 is secured to the forward portion of the frame 2 and coupled to the rear wheels 5 through a conventional gear transmission unit 7 to supply power to the rear wheels 5 and move the truck 3.

A cab 8 is secured to the forward portion of the frame 2 enclosing the engine 6 and the various steering and riding components of the truck 3 and provides a protective enclosure for the truck operator, not shown.

The truck 3 is generally representative of vehicles which are presently made to carry a mixing drum 1 and the load or batch of concrete, not shown. The particular truck 3 is generally typical of various commercially available motor trucks although the various construction details may vary considerably. Generally, however, the back frame portions are formed substantially identical to each other to accommodate the various containers and structures which are conventionally manufactured and secured to the trucks by others.

The mixing drum 1 is generally an elongated tapered cylinder having an outer, tear drop configuration.

A plurality of circumferentially distributed spiral vanes 9 are welded within the mixing drum 1 to discharge or to mix the concrete, not shown, in accordance with the direction of rotation of the drum 1, as subsequently described. The back end of the drum 1 is formed with an opening 10 through which concrete is selectively admitted and discharged. A hopper 11 is mounted in communication with the opening 10 to direct concrete into the drum 1 and an arcuate discharge chute 12 is pivotally mounted immediately below opening 10 to direct discharging concrete to the desired location. An inspection hatch 13 is provided in a central portion of the drum 1 to allow inspection of the interior of the drum 1 and the concrete, not shown. Hatch 13 may also be employed for charging drum 1.

The mixing drum 1 is rotatably supported upon the back portion of the frame 2 by a forward drive and bearing unit 14 and a rear bearing unit 15. A pair of Z-bars 16 are spaced in accordance with the members of frame 2 and welded or otherwise secured to the bearing units 14 and 15. The bearing units 14 and 15 are secured to frame 2 with the Z-bars 16 resting on the adjacent frame members to support drum 1 extending longitudinally of the truck 3 with the head of the drum 1 adjacent the rear of cab 8.

The rear-bearing unit 15 supports the back end of the mixing drum 1 above the head of the drum to bias the concrete, not shown, to the forward portion of the mixing drum 1 and thus maintain the maximum possible weight toward the forward or front part of the truck 3 and thus on the front steering wheels 4.

The mixing drum 1 is thus adapted to be mounted on any one of the various commercially available trucks and to be remounted upon a new truck incident to damage or obsolescence of truck 3.

Z-bars 16 are secured to the truck frame 2 by a plurality of standard bolt and nut clamp assemblies 17 to tie the back bearing unit 15 to the truck frame 2.

The illustrated bearing unit 15 is generally similar to that shown in the previously referred to U.S. Patent No. 2,696,371 and comprises a box-like cross brace 18 forming a bearing pedestal which extends upwardly and slightly forwardly from the rear end of the Z-bars 16 and the frame 2 adjacent the rear part of the mixing drum 1. A pair of laterally spaced rollers 19 are rotatably mounted on the upper end of the cross brace 18 to rotatably support the rear or back end of the mixing drum 1. A ring trackway 20 is secured or otherwise formed on the outer circumference of the mixing drum 1 in alignment with the rollers 19. A shield and bracket support 21 encircles the trackway 20 as an extension from the cross brace 18.

A pair of rearwardly projected brackets 22, of which only one is shown, are secured to opposite sides of the shield 21 and project rearwardly of the back end of the mixing drum 1 adjacent the opening 10. The hopper 11 and chute 12 are secured to brackets 22 for support.

The forward drive and bearing unit 14 is secured to the truck frame 2 to support the front end of the drum 1.

in the illustrated embodiment of the invention as follows.

Referring particularly to FIGS. 1-3, a box-like arculate bridge member 23 constituting a lateral mounting brace is secured between a pair of laterally spaced end or junction plates 24 which extend downwardly immediately adjacent the outer walls of the frame 2. The plates 24 flare forwardly and rearwardly of the bridge member 23 and are secured to the frame 2 by a plurality of bolts 25 to transmit the drum load to the frame 2. A triangular foot member 26 constituting a load distributing brace is welded to the undersurface of the bridge member 23 and the adjacent plate 24 and rests on the upper wall of the corresponding portion of frame 2 to distribute the load. The plates 24 are welded to the forward end of the Z-bars 16 to tie the forward bearing 14 to the rear bearing unit 15. A portion of the top wall of the Z-bars 16 is removed as at 27 to accommodate the rearwardly flared portion of plate 24.

A supporting socket member 28 of a two-piece ball-type socket 29 includes a depending bracket 30 which is welded to the top and the rear walls of the bridge member 23 midway between the plates 24. An upper retaining socket member 31 is releasably bolted to the bearing socket member 28 by a pair of oppositely disposed bolts 32, which extend through suitable openings in the member 28 and thread into correspondingly tapped openings in the retaining member 31. The bearing member 28 is provided with a hemispherical recess opening vertically and rearwardly upwardly toward the mixing drum 1. A bearing ball 33 is disposed within the hemispherical recess and pivotally clamped therein by the retaining socket member 31 which has a correspondingly shaped recess.

The bearing ball 33 includes an integral shank 34 which extends vertically upwardly therefrom with the axis of the shank and bearing ball lying in a plane which is perpendicularly related to the axis of the mixing drum 1. The shank 34 is secured within a corresponding opening in the forward drive and bearing unit 14. An encircling flange 35 is welded to the shank 34 adjacent the bearing ball 33 and is bolted as by bolts 36 to the forward drive and bearing unit which is thereby pivotally secured to the truck frame 2.

The bearing ball 33 in combination with the rollers 19 establish a three-point suspension for the mixing drum 1 and prevent the twisting of the truck frame 2 from being transferred to the forward bearing unit 14. Consequently, high stresses in the frame of the front bearing unit 14 are prevented.

In the illustrated embodiment of the present invention, the forward bearing unit 14 is a multi-cylinder, radial hydraulic motor which constitutes the forward rotating support for the mixing drum 1 and the power source to rotate the mixing drum 1.

The bearing unit 14 generally includes a ring-shaped motor housing 37 to which the bearing ball 33 is rigidly secured by flange 35 and bolts 36. A front closure and bearing plate 38 is removably secured to the ring-shaped housing 37 by bolts 39 to removably close the forward opening of the housing. An integral rear closure and bearing plate 40 closes the drum side of the ring-shaped housing 37.

A drive or crankshaft 41 is rotatably secured within the housing 37 by a front bearing 42 centrally located in the front closure and bearing plate 38 and a bearing 43 which is centrally located in the integrally formed rear closure and bearing plate 40. The front bearing 42 is a conventional double roll radial bearing and the rear bearing 43 is a conventional tapered roller self-aligning roller bearing. As the bearings are conventional, no further description thereof is given.

The drive shaft 41 extends rearwardly through the bearing plate 40 in alignment with the axis of drum 1. The shaft 41 is rigidly coupled to the front end of the

mixing drum 1 to form the forward trunnion of the mixing drum 1 as follows.

Referring particularly to FIG. 3, a coupling hub 44 is secured to the forward wall 45 of the mixing drum 1. An annular plate member 46 is welded to the inner surface of the wall 45 and to the inner portion of the hub 44 to rigidly support the hub on the mixing drum 1. The coupling hub 44 and the rearwardly extending portion of the shaft 41 are correspondingly splined as at 47 to interlock the shaft 41 and drum 1 and cause simultaneous rotation. Suitable lock nuts 48 thread onto the innermost end of the shaft 41, which is correspondingly threaded, to lock the hub 44 on the extended end of the drive shaft 41. Consequently, rotation of the drive shaft 41 is transmitted to the mixing drum 1 to rotate the concrete, not shown, which is supported within the drum.

The crankshaft 41 is provided with a central axial passage 49 which extends the complete length of the crankshaft and which is adapted to be connected to a water tank, not shown, which may be supported in any suitable manner on the truck, the forward bearing unit 14 or the like. In the illustrated embodiment of the invention, the opposite ends of the central water passage 49 are closed by suitable cap assemblies 50 and 51 which are releasably secured to the crankshaft 41. The United States Patent 2,534,445 which issued to T. K. Hilkemeier on December 19, 1950, discloses a particularly satisfactory construction for a water connection which may be readily applied to the illustrated crankshaft 41.

The ball-type socket 29 is secured to the motor housing 37 by the ball shank 34 somewhat forwardly of the principal plane through the housing 37 to substantially vertically align the rear bearing 43 with the ball 33. The load forces transmitted to the frame 2 through the ball socket 29, particularly while braking the truck 3, include a horizontal component and a vertical component which combine into a resultant force extending angularly forwardly and downwardly. The movement of the ball socket 29 forwardly, as shown, brings the line between the bearing 43 and the ball 33 more nearly in alignment with the resultant force and improves the transfer of the horizontal and vertical forces to the frame 2.

Referring particularly to FIGS. 3 and 4, a disc crank 52 is integrally formed on the crankshaft 41 and extends radially within the housing 37. The disc crank 52 is a circular member eccentrically arranged with respect to the axis of the shaft 41 such that rotation of the crankshaft 41 and the integral disc crank 52 causes the true center of the disc crank to define a circle about the axis of rotation. The outer periphery of the disc crank 52 is axially flanged as at 53 to establish a relatively wide ring-like surface spaced from the outer wall of the housing 37. The disc crank 52 is adapted to be rotated by a plurality of fluid actuated pistons 54 which are slidably journaled within cylinders 55 radially aligned with the crank 52.

The illustrated fluid motor includes five cooperating pistons 54 and cylinders 55 which are successively powered to cause smooth and positive rotation of the crank 41. Although any number of cylinders can be employed, more than three cylinders are necessary to make the motor self-starting. An odd number of cylinders results in minimum variation in pressure for each revolution of the drum. Each piston and cylinder arrangement is identical in the illustrated embodiment of the invention and consequently only one is described in detail.

Each cylinder 55 is an elongated cup-shaped member which is secured within a tubular hub 56 formed in the motor housing 37 in alignment with the plane extending through the disc crank 52. The cylinder 55 includes an integral upper head 57 substantially closing the outer end of the cylinder. A stop ring 58 is secured within a suitable encircling recess on the inner portion of the cylinder 55. The ring 58 extends radially from the cylinder 55 and mates with a corresponding recess formed on the

inner edge of the tubular hub 56 to prevent or limit the outward movement of the cup-shaped cylinder. A C-shaped clamp 59 encircles the cylinder 55 immediately adjacent the outer end of hub 56 and rests or engages the outer end surface of the hub. The adjacent upper edge of clamp 59 and an adjacent enlargement of the cylinder 55 are provided with correspondingly chamfered edges 60 such that tightening of the clamp prevents or limits inwardly movement of the cylinder 55 and rigidly clamps the cylinder within the hub 56.

A suitable opening 61 is provided in the head 57 of each cylinder 55 to receive a fluid line 62 through which a fluid 63, shown in FIG. 4, is sequentially selectively admitted and discharged from the cylinder 55 to reciprocate the pistons 54, and drive the disc crank 52 and attached crankshaft 41 as more fully described hereinafter.

The piston 54 is generally a cup-shaped member which is slidably supported within the cylinders 55. Oil rings 64 substantially seal the sliding surfaces between the piston 54 and the inner wall of the cylinders 55. A piston or connecting rod 65 is pivotally secured to the piston 54 and slidably coupled to the disc crank flange 53.

The piston end of connecting rod 65 and the adjacent surface of the piston 54 are correspondingly spherically recessed to receive a pivot ball 66. A ring retainer 67 is secured within the piston 54 and in engagement with an enlargement 68 on the inner end of the piston rod by a suitable coil spring 69 and a split ring 70 to pivotally and resiliently couple the rod 65 to the piston 54.

The opposite end of the piston rod 65 is provided with an integral triangular shoe 71 having a bearing portion 72 which corresponds generally to the width of the crank flange 53 and extends circumferentially of the crank 52. A radial projection 73 is formed on the outer periphery of one side of the connecting rod shoe 72 and a split clamp ring 74 having an inwardly opening recess is disposed over the projection to radially couple the connecting rods 65 in bearing engagement with the crank 52.

Referring particularly to FIG. 4, the hydraulic motor is shown with the top and upper right cylinders 55 connected to a source of high pressure as subsequently described to receive fluid 63 and to move the pistons 54 and attached bearing shoes 72 inwardly. The line of force on crank 52 is off center with respect to shaft 41 and thus the crank 52 rotates in a counterclockwise direction. The upper left cylinder 55 is on dead center with its line of force aligned with the center of shaft 41 and the true center of crank 52. The lower left and right cylinders are connected to the low pressure side of the source, as subsequently described, to discharge the actuating fluid 63 and allow inward movement of the corresponding pistons 54. The cylinders receiving and discharging fluid are out of phase or step with each other to provide overlapping of the power cycles. The cylinders 55 are sequentially powered with the slight overlap in the power cycle of adjacent cylinders to establish a smooth and continuous rotation of the crank 52.

To reverse the direction of rotation, with the motor in the state illustrated in FIG. 4, the two lower cylinders 55 are connected to the high pressure side of a source and the top and upper right cylinders are connected to the low pressure side of the source. Thus, the direction of rotation is controlled by the sequential direction in which fluid is applied to the successive cylinders 55. Consequently, successive actuation of the pistons 54 by the incoming fluid 63 which is admitted via fluid lines 62 and the fluid openings 61 continuously shifts the position of the several shoes 72 and causes rotation of the crank 52 and the attached shaft 41.

The connecting rods 65 oscillate slightly about the ball pivot 66 in accordance with the superimposed straight line motion affected by the successive cylinders to allow the simultaneous movement of the shoes 72 in two relative directions.

A portion of the incoming fluid 63 to the cylinder 55 is used to establish forced lubrication between the shoes 72 and the crank flange 53 and to thereby reduce the friction forces and allow smooth rotation of the crank 52. Radially aligned oil passages 75, 76, and 77 are respectively formed in the piston 54, the pivot ball 66 and the connecting rod 65 to allow a relatively minute quantity of incoming fluid 63 to flow radially into the interface area between the bearing portion 72 of shoe 71 and the crank flange 53. The lubricating oil flows between the bearing portion 72 of shoe 71 and the crank flange 53 of crank 52 and discharges into the housing 37.

An oil drain 78 is secured to the lower end of the housing 37 to drain off the accumulated lubricating fluid and to return it into the system, as subsequently described.

The hydraulic motor thus serves to rotate the mixing drum 1 as well as to simultaneously constitute the forward bearing support for the mixing drum.

Referring particularly to FIGS. 2 and 3, a pair of superposed rigid torque resisting rods 79 and 80 are pivotally secured at one end to the housing 37 and at the opposite end to one of the bearing plates 24 by suitable knuckle joints 81. Each of the knuckle joints 81 includes a pair of inwardly extending pins 82 secured to the end of rods 79 and 80 and to a bearing ball 83. The bearing balls 83 are mounted for universal pivotal movement within corresponding spherically surfaced openings formed in a pair of mating lugs 84 which are respectively welded to the housing 37 and mounting plate 24. The torque rods 79 and 80 prevent lateral swinging of the drum and stabilize the mounting of the drum 1 on pivot support 29.

Referring particularly to FIGURES 1, 3 and 6, the actuating fluid 63 supplied to the hydraulic motor cylinders 55 is preferably a low-velocity, high pressure fluid from a suitable fluid pump 85 driven by the truck engine 6. High working pressures create less heat loss, eliminating the need for a heat exchanger, and are generally more efficient. Further, the distributing system is simpler and the hydraulic motor can within practical limits be reduced in size. As a practical economic construction, 4000 pounds per square inch presently appears to provide the best design.

The pump 85 is mounted on the truck frame 2 adjacent the engine 6. A belt connection 86 connects the fluid pump 85 to a forward engine crankshaft extension for operation incident to running of the truck engine 6. The fluid pump 85 is preferably a variable-displacement reverse-flow type pump of the swash plate design which is commercially available and is adapted to establish a low velocity, high pressure fluid flow. The pump 85 is therefore shown by a conventional graphical symbol in FIG. 6.

A fluid distributing valve 87, mounted on the hydraulic motor housing 37, is connected to the output of the fluid pump 85 by a pair of transporting flexible conduits 88 and 89. The conduits 88 and 89 are alternately selectively connected to the high and low pressure sides of the pump 85 for forward and reverse rotation of the mixing drum 1.

Referring particularly to FIGS. 3 and 5, the valve 87 includes a housing 90 which is secured within an opening in the motor-housing 37. A pair of spaced inlet-outlet ports 91 and 92 are provided in the exterior wall of the housing 90 and are coupled to the fluid pipes 88 and 89 and a plurality of distributing ports 93 are provided and connected to the several fluid lines 62 for carrying the fluid to cylinders 55. A rotatable valve drum 94 is journaled within the distributing valve housing 90 between the ports 91 and 92 and the ports 93. The drum 94 includes suitable distributing passages 95 which are adapted to successively connect the inlet-outlet ports 91 and 92 to the individual distributing ports 93 and thus to the cylinders 55. A drive shaft 96 is secured to the valve drum 94 and extends outwardly through housing 90 and into the

motor housing 37. A gear 97 is secured to the extended end of the shaft 96 and is connected by a suitable idler gear 98 to a drive gear 99 which is secured about the hydraulic motor shaft 41. The gear 98 is rotatably mounted on the adjacent portion of the hydraulic motor and establishes timed synchronous rotation of the valve drum 94 with shaft 41. Consequently, as the motor shaft 41 rotates the valve drum 94 is slowly rotated to successively connect the inlet-outlet ports 91 and 92 to the distributing ports 93 to simultaneously supply high-pressure fluid 63 to certain of the cylinders 55 and to withdraw fluid from other cylinders.

The direction of rotation of the motor is determined by which of the inlet-outlet ports 91 and 92 is connected to the high pressure side of the pump 85. If port 91 is connected to the high pressure side of pump 85, the sequence of fluid application is in one direction, assumed arbitrarily to be in a counterclockwise direction as viewed in FIGURE 4. Then, if port 92 is connected to the high pressure side of the pump 85, the sequence of fluid application to the cylinders 55 is in a reverse or clockwise direction. Consequently, the direction of rotation of drum 1 is easily and readily controlled in accordance with the operation of pump 85.

The illustrated rotary valve is relatively simple and eliminates the shocks created by the conventional spool valve, the results of which are difficult and expensive to control.

The hydraulic circuit may be formed in any conventional or desired manner. A simplified diagrammatic hydraulic flow circuit is shown in FIGURE 6 for purposes of fully and clearly explaining the functioning of the present invention.

Referring particularly to FIGURE 6, the illustrated circuit is a closed-loop hydraulic system extending between the hydraulic motor and bearing unit 14 and the pump 85. The truck engine 6 is connected to drive the fluid pump 85 which in turn is connected to the distributor valve 87 by the conduits 88 and 89.

A control lever 100 is connected to the pump 85 by a suitable mechanical linkage or the like, as shown in FIG. 1, and controls the direction of fluid flow through the pump and consequently determines the high and low pressure connection of the pump 85 to conduits 88 and 89. The control lever 100 has a forward position, shown in phantom to the right in the FIG. 6, and it is assumed for purposes of illustration that in this position, fluid flow is through the pump 85 from conduit 89 to conduit 88 and consequently conduit 88 is connected to the high pressure side of the pump 85 and conduit 89 is connected to the low pressure side of the pump. The control lever 100 has a reverse position, shown in phantom to the left in FIG. 6, in which position a reverse fluid flow is established by pump 85 and the conduit 88 is now connected to the low pressure side of the pump and the conduit 89 is connected to the high pressure side.

The control lever 100 when centrally located between the forward position and the reverse position, as shown, constitutes a neutral position wherein the conduits 88 and 89 are effectively disconnected from the pump 85 and lock the fluid within the motor circuit.

The intermediate positions of the control lever 100 between the neutral position and the full forward or reverse position throttles the fluid pressure and thereby regulates the speed of rotation of the mixing drum 1. This provides a reliable stepless control giving an infinite number of speeds within a predetermined range.

Further, when the hydraulic motor is operating in one direction and is to be quickly reversed, the mixing drum 1 is braked and establishment of high shock forces is eliminated. As the operator moves the control lever 100 toward the neutral position, the fluid flow to the cylinders 55 is progressively reduced and the motor speed reduced accordingly. When the neutral position is reached, the fluid 63 is locked in the circuit and brakes the drum 1 to

prevent large shock forces incident to the reverse positioning of the lever 100.

The control of the direction and speed of rotation of the mixing drum is therefore simple and cannot be operated in a manner to cause damage to an expensive coupling system as in conventional mixing units. Consequently, unskilled personnel can be employed to operate the mixing drum.

The control lever 100 constituting a manual control is mounted within the cab of the truck 3 and connected to pump 85 by a suitable coupling cable, not shown, to allow ready and convenient location of the control adjacent the operator, not shown.

A small oil reservoir 101 is mounted on the truck 3 and connected to the crankcase drain 78 to collect the lubricating oil by-passed through the hydraulic motor, as previously described. Because the hydraulic power system to the motor and bearing unit 14 is a closed loop, the reservoir 101 is small and does not add appreciably to the weight of the truck and mixing components.

A make-up pump 102, shown in FIG. 6, connects the oil reservoir 101 to the fluid conduits 88 and 89 to make up or return the withdrawn fluid into the system and thereby to maintain a constant volume in the closed loop between the motor and the pump 85. Check valves 103 and 104 are connected in parallel between each of the conduits 88 and 89 and the make-up pump 102 to prevent a reverse flow of fluid from the corresponding conduits. Consequently, the volume of fluid within the closed loop driving the hydraulic motor is maintained at a constant value.

A suitable pulley connection 105 connects the make-up pump 102 to the engine 6 for operation of the make-up pump whenever the hydraulic motor is operated. The pump 102 and connecting conduits are only shown in FIG. 6 for clarity of illustration.

The present invention provides a motor for directly driving the mixing drum 1 from the truck engine 6 without the necessity of complicated power transmission apparatus which is both difficult to install and maintain. The speed of the mixing and discharging can be independently established with a continuous and fine adjustment within a relatively wide range through a simple and economic control unit. The term mixing is broadly employed in the present application to define the conventional mixing of the aggregate to form the concrete and also the normal agitation of a premixed concrete which is disposed within the drum for transportation.

Thus, the drum may readily be rotated from 0 up to 15 or 18 revolutions per minute while maintaining normal engine speed. The drum 1 can therefore be rapidly rotated to discharge the concrete while the truck is moved forwardly at a relatively low speed.

The direct connection of the hydraulic pump to the engine establishes independent operation of the mixing drum and the propulsion of truck 3. The starting and the stopping of the truck and the changing of the truck driving gears can be readily and rapidly controlled in the most advantageous manner. Further, the truck-mounted mixer of the present invention can be operated without any substantial training without clashing of the gear and destruction of the clutch.

The combined bearing and driving motor of the present invention allows a most advantageous distribution of the weight of the truck, mixing apparatus and the concrete contained therein upon the truck wheels such that the percentage of the total weight applied to the rearward wheels is maintained at a minimum. Consequently, an increased total load can be carried.

The mixing drum of the present invention is readily mounted on any conventional truck vehicle and is readily interchanged to a new truck whenever necessary.

The direct interconnection of the hydraulic motor as a forward bearing unit reduces the number of separate components mounted on the truck and interconnected

with the drum and permits a more modern design of a truck mounted mixer.

Various modes of carrying out the invention are contemplated as being within the scope of the following claims particularly pointing out and distinctly claiming the subject matter which is regarded as the invention.

I claim:

1. A drive mount for a tubular shaped mixing drum having a closed end for mounting on the frame of a truck, which comprises a hydraulic motor including housing and a driven shaft rotatably mounted in the housing, means to connect the driven shaft to the closed end of the mixing drum to rotate the mixing drum, and a universal pivot support secured to the housing and having attachment means for securing to the frame of the truck to transmit the concentrated load presented at the closed end of the drum directly to the frame.

2. A drive mount for a tubular shaped mixing drum having a closed end for mounting on the channel frame of a truck, which comprises a hydraulic motor including a housing and a driven shaft rotatably mounted in the housing, means to connect the driven shaft to the mixing drum to rotate the mixing drum, a universal pivot support secured to the housing, and attachment means secured to the pivot support and including side plate members extending downwardly adjacent the outer surfaces of the frame and having bolt receiving means for bolting of the side plate members to the frame of the truck to transmit the concentrated load presented at the closed end of the drum directly to the frame in the assembled position.

3. A truck-mounted concrete mixer including a concrete mixing drum adapted to be rotatably mounted on a frame of a conventional motor truck having a running control transmission and an engine operatively connected to drive said control transmission, said mixing drum being closed at its forward end and open at its rearward end, which comprises a variable displacement reversible-flow high-pressure pump operatively connected to be driven by said truck engine independently of said running control transmission, control apparatus arranged to control said pump as to volume and direction of fluid flow therefrom, bearing means disposed to rotatably support said open rearward end of said drum, a multi-radial-cylinder hydraulic motor having a rotating shaft secured to the closed forward end of the drum, a ball and socket joint disposed to support said hydraulic motor on said motor truck at a single point for universal pivoting movement thereon, a torque-resisting strut interposed between said hydraulic motor and said truck to stabilize said motor and said mixing drum in operating position while permitting relative movement between said mixing drum and said truck to accommodate deflections of said truck, and flexible fluid conduits sequentially connected between said high pressure pump and the cylinders of said hydraulic motor to drive said mixing drum in either direction at desired speed incident to predetermined actuation of said control apparatus.

4. In a transit mixer for transporting and mixing a batch of concrete or the like including a motor truck having a drive engine on one end of the truck and a mixing drum rotatably mounted on the opposite end of said truck for receiving a batch of concrete to be transported, a high pressure reversible hydraulic motor having a rotating member rotatable at the velocity range of the mixing drum, said rotating member being directly connected to the engine end of said mixing drum to directly rotate the drum at the same angular velocity as the motor, a high pressure variable capacity pump operatively connected to be driven by said truck engine and to drive said hydraulic motor, and control apparatus operatively connected to adjust said variable capacity pump in a manner to regulate the speed and direction of rotation of said mixing drum.

5. In a transit concrete mixer of the type having a

rotatable mixing drum carried by a self-propelled vehicle having a driving engine, a variable capacity reversing flow pump connected to be driven by said vehicle driving engine independently of the vehicle propulsion connection of said engine, manually operable control means arranged to adjust said pump to supply pressure fluid at selected rate in selected direction of flow from said pump, a hydraulic motor directly connected to said mixing drum to rotate the drum at the same velocity as the hydraulic motor, fluid conduit means operatively connecting said variable capacity reversing flow pump to said hydraulic motor whereby said rotatable mixing drum may be driven in either direction as predetermined speed selectively by controlling said pump independently of the propulsion of said vehicle, and a universal joint secured to the truck and the hydraulic motor and constituting the support for the adjacent end of the drum.

6. In a motor-truck transit mixer having a driving engine on one end of the truck and having a concrete mixing drum rotatably mounted on the opposite end of the truck for containing a batch of concrete and transporting the batch of concrete, a slow speed hydraulic motor having a motor housing and a power rotated member directly connected to said mixing drum adjacent said engine, a ball socket joint mounting said motor housing on said truck to rotatably support the drum, a variable capacity hydraulic pump mounted adjacent the engine and operatively connected to be driven by said truck driving engine, fluid conduit means interconnecting said pump and said hydraulic motor to selectively drive the rotatable member of the motor and attached drum incident to said pump being driven by said engine, and control means operatively connected to adjust the pumping capacity of said pump thereby to regulate the fluid pressure to said motor to regulate the speed of rotation of said mixing drum.

7. In a transit concrete mixer, including a vehicle having spaced running wheels secured to a yieldable frame subject to deflection when operating over uneven terrain, a mixing drum closed at one end and open at the other end to receive a batch of concrete to be mixed and transported and adapted to be secured to the frame close to certain running wheels and spaced from other running wheels, a motor provided with a protruding drive shaft that is rigidly fixed to the closed end of said mixing drum in a manner to rotatably support said drum end and to rotate the drum, means arranged to support said motor on said vehicle frame for universal relative movement to accommodate deflection of said frame, means arranged to support said end of said drum for rotation on said frame in a manner to accommodate deflection of said frame, and a torque arm connected between said frame and said universally mounted motor to maintain said motor in position relative to said frame for supporting said closed end of said drum for rotation on said frame, the arrangement being such that said drum may be rotated as said vehicle traverses uneven terrain without detrimental effects upon said drum or its driving motor resulting from deflection of said yieldable frame.

8. In a transit concrete mixer including a wheeled conveyance having a yieldable frame, a mixing drum for transporting and mixing concrete, said drum being open at one end and presenting an axially disposed shaft at the other end, a pair of spaced rollers rotatably mounted on said yieldable conveyance frame in a position to support the open end of said mixing drum, and a drum driving motor comprising a stator and a driven rotor mounted with said driven rotor rigidly connected to said shaft of said drum and with said stator mounted for universal movement on said yieldable conveyance frame and constituting the support for the corresponding end of the drum, the arrangement being such that said mixing drum and said motor are rigidly interconnected as a unitary structure that is mounted at three points on said yieldable

frame whereby weaving of said yieldable frame may occur as said conveyance moves over uneven surfaces.

9. A drive mount for a tubular shaped mixing drum having a closed end for mounting on the channel frame of a truck, which comprises a hydraulic motor including a relatively stationary housing and a driven shaft rotatably mounted in the housing, means to connect the driven shaft to the mixing drum to rotate the mixing drum, a ball pivot support having a ball member and a socket member one of which is secured to the housing, a lateral mounting brace secured to the opposite member of the pivot support, and junction plates secured to the brace and adapted to project downwardly adjacent the outer surfaces of the frame with the brace resting on the frame and adapted to be bolted to the frame of the truck to transmit the concentrated load presented at the closed end of the drum directly to the frame.

10. A drive mount for a tubular shaped mixing drum having a closed end for mounting on the channel frame of a truck, which comprises a hydraulic motor including a relatively stationary housing and a driven shaft rotatably mounted in the housing, means to connect the driven shaft to the mixing drum to rotate the mixing drum, a ball pivot support having a ball member and a socket member one of which is secured to the housing, a lateral mounting brace secured to the opposite member of the pivot support, junction plates secured to the brace and projecting downwardly adjacent the outer surfaces of the frame in the assembled position and being bolted to the frame of the truck to transmit the concentrated load presented at the closed end of the drum directly to the frame, and load distributing braces secured to the mounting brace immediately adjacent said junction plates and resting upon the adjacent members of the channel frame of the truck.

11. In a concrete mixer having a generally tubular mixing drum mounted on a truck frame and rotated about the axis of the drum, a radial hydraulic motor having a housing with a plurality of circumferentially dis-

tributed cylinders lying in a common plane and pistons in said cylinders directly coupled to drive a crank and a shaft centrally journalled in forward and rear bearings in said housing, said shaft extending perpendicular to said common plane, means to rigidly couple the motor shaft to the drum in alignment with the drum axis, universal support means secured to said truck frame and to said motor in slightly spaced forward relation to said common plane to establish a substantially vertical line extending between the rear bearing for said shaft and said support means, and bearing means secured to said frame to rotatably support the opposite end of the mixing drum with the axis of the drum extending downwardly therefrom in alignment with the motor shaft.
